UNITED STATES PATENT OFFICE

ALBERT BELA BAUMGARTEN, OF ASTORIA, NEW YORK

PORCELAIN-VENEER DENTAL CROWN

Application filed August 23, 1928. Serial No. 301,602.

This invention relates generally to veneered dental crowns, and more particularly, to dental crowns having a veneer of porcelain or similar material.

Veneered gold crowns, as now commonly used, are usually formed by inserting a veneer in a recess of the crown, and by swedging a rim of gold around the edges of the veneer; which results in the objectionable display of a rim of metal around the veneer. It is usual, too, to subject the veneered crown to heat for the purpose of securely uniting the veneer to the gold; but, the heating frequently discolors the veneer and renders the veneered crown unfit for use.

The object of the present invention is to eliminate the objections just noted, and to form veneered dental crowns in which the porcelain veneer is locked to the crown without the intervention of heat and with practically all of the objectionable facial display of gold eliminated.

Other objects of the invention will become apparent as the detailed description proceeds.

In the drawings:

Figure 1 is a front elevation of a veneered dental crown embodying this invention;

Figure 2 is a vertical section on the line 2-2 of Figure 1;

Figure 3 is a section similar to that shown in Figure 2, but with the veneer partly removed from its supporting crown;

Figure 4 is a horizontal section on the line 4-4 of Figure 2;

Figure 5 is a perspective of a crown forming part of a modified form of the invention;

Figure 6 is an elevation of a veneer adapted to be used with the crown shown in Figure 5;

Figure 7 is a front elevation of another modification of the invention;

Figure 8 is a vertical section taken on the line 8-8 of Figure 7;

Figure 9 is a perspective view of the crown shown in Figures 7 and 8, but with the veneer removed therefrom;

Figure 10 is a central vertical section through a further modified form of the in-

vention, showing a veneer partly applied to a crown;

Figure 11 is a central vertical section of a completed crown of the type shown in Figure 10; and

Figure 12 is a horizontal section on the line 12-12 of Figure 11.

In the form of the invention shown in Figures 1 to 4, the crown 1 of gold, or other suitable material, is shaped to fit the tooth being 60 crowned. The front of the tooth is designed to receive a veneer 2 of porcelain or other material adapted to simulate a natural tooth.

In order to receive and hold the veneer the lower edge of the veneered part of the 65 crown is turned upward to form a recess 3, and this recess is continued around the crown to terminate in recessed vertical shoulders 4 and 5 adapted to receive the substantially vertical edges of the veneer 2.

The vertical shoulders 4 and 5 diminish as they approach the top of the crown so that ordinarily the veneer might be slit longitudinally in said recesses to position the lower edge 6 thereof in the recess 3. This construction would lock the veneer against downward and lateral movement relative to the crown, but it would not prevent the top of the veneer being moved out from the top of the crown.

In order to lock the veneer securely to the crown against movement in all directions, the upper edge of the veneer is provided with a recess 7 beveled outwardly from the crown. The crown is provided with a lug 8 at the top edge thereof and adapted to be bent into said recess to form a dovetail locking tongue for securing the veneer to the crown.

It will be noted that the lug 8 extends below the top of the veneer and of the crown so that it cannot be bitten clear through and thereby break the locking contact between the crown and the veneer.

As will be clear from inspection of Figure 4, the veneer extends around the front of 95 the tooth to the widest part of the crown. By this construction the veneer will practically contact with the adjacent tooth and will prevent exposure of the gold or other material 100 except at the root of the crown, which is a

part that is ordinarily covered by the lips of the person. The slight exposure of gold, or similar material, in the recess 7 has very little effect on the artistic display of the tooth and would ordinarily be taken as a filling of a small cavity in a natural tooth.

The modification shown in Figures 5 and 6 is substantially the same as that shown in Figures 1 to 4, except that the veneer is provided at the top edge thereof with outwardly beveled recesses 9 and 10 adapted to receive the lugs 11 and 12, respectively, formed on the upper edge of the crown 18.

A further variant of the invention is shown in Figures 7, 8 and 9. In this form, the locking means between the crown and the veneer is placed somewhat centrally of the tooth and not at the upper edge thereof.

The crown 14 is provided with a veneer receiving recess similar to the recesses shown in the other modifications. The veneer itself, however, is provided with a countersunk aperture 15 at any desired position in the body thereof and away from its edges. The crown is provided with a lug 16 positioned to correspond with the position of the aperture 15 in the veneer 17 and adapted to be passed through said aperture and be hammered out to fill the countersunk aperture and thereby lock the veneer to the crown.

A further modification of the invention is illustrated in Figures 10, 11 and 12. In this form, the crown 18 has its lower front edge provided with a recess 19 and is upturned to form a locking lip 20 adapted to enter a corresponding locking recess 21 in the veneer 22.

The veneer 22 may be secured to the crown 18 by any of the means used to secure the veneer to the crown in the previously described forms of this invention. As shown, the veneer 22 is locked to the crown 18 by means of a lug 23 formed on the top of the crown and adapted to enter and fill a recess 24 formed on the upper edge of the veneer 22.

In all the forms of the invention disclosed herein, it must be understood that the porcelain or other veneer is secured by a suitable cement in the recesses formed in the crown, in addition to being locked to the crown mechanically by the dovetailed recess and lug construction illustrated and described herein. In all the forms of the invention, it is to be understood, too, that the porcelain, or other veneer, extends sufficiently far around the crown as to avoid exposure of any rim around the crown except at the root thereof. The locking lugs may be arranged in any desired position in order to give them the appearance of very small fillings in a natural tooth.

What I claim is:

1. A veneered dental crown comprising a metallic hollow crown shaped to fit a tooth and having its lower edge upturned to form a recess, a tooth-shaped veneer having its lower edge formed to fit in said recess, and

means projecting from said crown through said veneer to lock the veneer to the crown.

2. A veneered dental crown comprising a metallic hollow crown shaped to fit a tooth and having its gingival portion upturned to form a recess, a tooth-shaped veneer having its lower edge formed to fit said recess and being provided with a countersunk aperture, and a lug extending from said crown and filling said aperture to lock the veneer to the crown. 70

3. A veneered dental crown comprising a metallic hollow crown shaped to fit a tooth and having its gingival portion upturned to form a recess, a tooth-shaped veneer having its lower edge formed to fit said recess and being provided with an outwardly beveled notch in the occlusal edge thereof, and a lug extending from said crown and filling said notch to lock the veneer to the crown. 75

In testimony whereof I affix my signature. 80

ALBERT BELA BAUMGARTEN.
